United States Patent

Des. 238,895

Patented Feb. 17, 1976

238,895

GASOLINE PUMP

Edward Albright, Paris, France, assignor to
SATAM Industries, La Courneuve, France

Filed June 27, 1974, Ser. No. 483,550

Term of patent 14 years

Int. Cl. D20—01

U.S. CL. D52—2 A

FIG. I

FIG. 2

FIG. 3

FIG. 1 is a front elevational view of a gasoline pump showing my new design, the rear being a mirror image thereto;

FIG. 2 is a top plan view thereof;

FIG. 3 is a right side elevational view thereof, the left side being a mirror image thereto.

I claim:

The ornamental design for a gasoline pump, as shown and described.
